UNITED STATES PATENT OFFICE.

WILLIAM T. HEDGES, OF CORNING, NEW YORK, ASSIGNOR TO CORNING GLASS WORKS,
OF CORNING, NEW YORK, A CORPORATION OF NEW YORK.

DESIGN FOR A COOKING DISH.

Application filed September 17, 1921. Serial No. 501,457. Term of patent 14 years.

To all whom it may concern:

Be it known that I, WILLIAM T. HEDGES, a citizen of the United States, residing at Corning, in the county of Steuben and State of New York, have invented a new, original, and ornamental Design for a Cooking Dish, of which the following is a specification, reference being made to the accompanying drawings, forming part thereof.

Figure 1 is a perspective view, showing my new design for cooking dish.

Figure 2 is a fragmental view in section, of the cooking dish, as shown in Figure 1.

I claim:

The ornamental design for a cooking dish, as shown.

WILLIAM T. HEDGES.
